UNITED STATES PATENT OFFICE.

JOHN J. REGAN, OF BOSTON, MASSACHUSETTS, ASSIGNOR TO THE LAMSON COMPANY, OF SYRACUSE, NEW YORK, A CORPORATION OF MASSACHUSETTS.

CENTRAL-STATION APPARATUS.

Application filed May 2, 1923. Serial No. 636,079.

To all whom it may concern:

Be it known that I, JOHN J. REGAN, a citizen of the United States of America, and resident of Boston, in the county of Suffolk and State of Massachusetts, have invented new and useful Improvements in Central-Station Apparatus, of which the following is a specification.

This invention pertains to carrier despatch systems, and relates more particularly to improvements in the central station of such a system.

The capacity of the central station of a carrier despatch system must necessarily increase as the establishment grows and the number of clerks or sub-stations, herein-after referred to as "sending stations" is correspondingly augmented, but in many of the older installations, lack of available space for expansion makes it exceedingly difficult, if not impossible, to provide for the greater number of operators usually deemed necessary for performing a larger number of transactions. This is particularly apparent in those establishments where carrier systems of the cable type are employed, as this type of system is much less amenable to crowding than is a system of the pneumatic type, for example, and presents greater difficulties in installation where head room is limited and where many and abrupt angles must be turned. Thus, if it is not possible to increase the space for installation, the most feasible alternative appears to be to decrease the size of the individual units comprising the central station so as to make a more compact arrangement. Compactness of arrangement when properly carried into effect, not only increases the capacity of the central station unit and makes for greater flexibility in operation by permitting one operator to care for more than the usual number of sending stations, but also allows a larger number of operators to perform the necessary transactions relating to the same group of sending stations without interference or confusion when the volume of business increases.

In accordance with the present invention, the sending devices particularly, and preferably the receiving devices, as well, of each central station unit are arranged so com-

pactly that an individual operator is able to perform a much greater number of transactions than usual with substantially no more hurry or exertion, while the new units take up so little floor space as compared with the usual arrangement that a greater number of operators may work efficiently in the same available space than has heretofore been possible.

Among the features contributing to this desirable result is an arrangement whereby the incoming carriers from a large number of outlying stations are automatically delivered, substantially in the order of their arrival, upon a table or shelf in front of the operator's station from which they may readily be picked up without requiring the manipulation of catches or other releasing means. A series of cable despatch terminals, corresponding to the several outlying stations, are disposed within convenient reach of the operators' stations, the carrier receiving opening of each terminal being disposed in either a vertical or horizontal plane directly opposite the operator's position so as to facilitate engagement of the carriers with the cables without undue exertion on the part of the operator. The delivery and despatch terminals corresponding to each sending station are arranged in the same vertical plane, with the delivery terminal behind the despatch terminal, thus allowing the corresponding pairs of tracks to approach the station at any desired height or heights above the level of the receiving table or shelf without interference with each other or requiring a large number of sharp bends or turns, thus facilitating the arrangement of the carrier receiving openings at the most convenient position for the operator.

A desirable embodiment of the invention is disclosed by way of example in the accompanying drawings, in which:

Fig. 1 is a plan view of one unit of a central station apparatus constructed in accordance with the present invention;

Fig. 2 is a front elevation, partly diagrammatic, of the apparatus shown in Fig. 1;

Fig. 3 is a vertical section substantially on the line 3—3 of Fig. 1;

Fig. 4 is a diagrammatic plan of a central station embodying one unit of the improved apparatus;

Fig. 5 is a diagrammatic end elevation of the structure shown in Fig. 4;

Fig. 6 is a vertical section to larger scale, on the line 6—6 of Fig. 1;

Fig. 7 is a fragmentary plan view of the parts shown in Fig. 6;

Fig. 8 is a front elevation;

Fig. 9 is a side elevation of a despatch terminal employed in the preferred form of the apparatus; and

Fig. 10 is a vertical section similar to Fig. 6, but illustrating a modification, and Fig. 11 is an enlarged front elevation of a despatch terminal used in the apparatus shown in Fig. 10.

Referring to Fig. 4, a central station is indicated generally by the numeral 1 having one unit 2 of operating mechanism positioned at one end thereof. While as herein shown but one unit is installed in the central station, it is to be understood that as many similar units may be installed as space will permit or occasion may demand.

Each operating unit preferably comprises a plurality of operators' stations 3, 4, 5, arranged at one side of an elongate desk 6. This desk comprises a working table or shelf 7, (Fig. 6) a recess or depression 8 for the reception of cashiers' tills or other appurtenances, and a table 9 upon which arriving carriers are deposited in front of the operators. This table is conveniently arranged somewhat below the level of the table 7 and if desired may be provided with a metallic facing 10 which serves to prevent rapid wear and at the same time facilitates the movement of carriers lengthwise of the table. The forward edge of the table may be provided with an upstanding flange or bead 11 formed of any suitable material, such for example as sheet metal, and which prevents carriers from dropping laterally from the table 9 into the till space 8.

The rear edge of the table or shelf 9 is defined by a vertical panel 12. Spaced to the rear of the panel 12 is a panel 13 from which in turn a similar panel 14 is spaced. The panels 13 and 14 define an elongate trough or channel 15 extending parallel to the shelf 9 but having its floor disposed in a plane somewhat above the plane of said shelf. The floor of the trough or channel 15 is formed by the upper runs 16, 17 of a pair of endless belt conveyors supported by the pulleys 18, 19; 20, 21, respectively. These belts are constantly driven in opposite directions so that their upper runs move away from the central part of the desk 6.

Adjacent to the opposite ends of the trough 15, openings are formed in the panel 13, and adjacent to the respective openings,

inclined deflectors 22, 23 are disposed across the trough 15 so as to divert carriers moving upon the respective belt conveyors and cause said carriers to pass forwardly through the openings in the panel 13. Forwardly and downwardly inclined chutes 24, 25 are associated with the respective openings and terminate substantially in the plane of the upper surface of the table 9.

At either end of the table 9 an elongate open trough or guideway is arranged, such troughs comprising the spaced side walls 26, 27; 28, 29, respectively. These troughs extend substantially in alignment with the longitudinal axis of the table 9 and their floors are formed by the upper runs 30, 31, respectively, of a pair of endless belt conveyors mounted upon pulleys 32, 33; 34, 35, respectively. These belt conveyors are constantly driven in opposite directions so that their upper runs move toward the center of the desk 6. The upper runs of these conveyors lie substantially in the plane of the upper surface of the table 9 so that carriers deposited upon the respective conveyors are moved in opposite directions onto the end portions of the table.

Each unit of the apparatus is intended to serve a series of outlying sending stations with which it is connected by conveyor tracks 36, 37, 38, 39, 40, 41, 42, 43, respectively, (Fig. 4) it being understood that the specific number of stations served by the apparatus may be varied as circumstances or experience indicate to be desirable. As the terminal portions of such pair of tracks are similar it is sufficient herein to describe but one in detail.

Referring more particularly to Figs. 6 and 7, the track 36 is shown as comprising the upper rails 36^a forming the despatch element along which carriers move from the central station to the clerk's station, and the lower rails 36^b forming the delivery element along which carriers move from the clerk's or sending station to the central station. The rails 36^a are arranged vertically above the rails 36^b, and the latter are bent at 44 to provide a vertical terminal portion which is supported upon a bracket 45 carried by the upper edges of panels 13, 14 respectively. The lower extremities 46 of the rails 36^b are bent (Figs. 2 and 7) so as to direct carriers delivered therefrom in the general direction of movement of the conveyor belt lying immediately beneath them. Thus the terminals at one end of the desk are bent to direct their carriers onto belt 16, while those at the other end are oppositely bent to direct their carriers onto the belt 17.

The ends of the rails 36^a are supported by a bracket 47 and just to the rear of the bracket the rails are spread to provide a horizontally disposed carrier receiving opening 48, (Figs. 1 and 7). The usual mechan-

ical accessories are provided for assuring the clamping of the carrier to the cable as the carrier is inserted through the opening but are not illustrated in detail. Preferably the terminals of all of the outgoing rails are arranged in the same horizontal plane, irrespective of the height at which they enter the station, thus facilitating the despatch of carriers but without substantially complicating the apparatus.

The driving cable comprises the run 51 associated with the tracks 36^b and extending from the clerks' or sending stations. The cable passes over the guide pulley 52 and extends downward at 53 and about the driving pulley 54, thence upwardly about the guide pulleys 55 and 56, then rearwardly below carrier receiving opening 48 and in parallelism with tracks 36^a to the sending or clerk's station. The pulley 55 may be dispensed with by suitably positioning pulley 56.

In the operation of the device, all carriers arriving from the sending stations drop freely from the ends of the corresponding delivery terminals into the trough 15 and onto one or the other of the belts 16, 17. The carriers are moved by these belts until they engage one or the other of the deflectors 22, 23 by which they are diverted forwardly onto the inclined chutes 24, 25. The carriers pass down these chutes onto one or the other of the belts 30, 31 and are then moved inwardly toward the center of the desk until they are delivered onto the upper surface of the table 9. If a carrier deposited upon the table is not immediately picked up by an operator, it will be pushed further along by the next carrier to arrive so that the order of arrival of carriers may readily be determined at any time by inspection of their arrangement upon the table 9. The operator, seated at one of the stations 3, 4 or 5, may pick up the carrier freely from the table 9 and after performing the desired transaction may return the carrier to the sending point by inserting it in the proper opening 48. As the despatch terminals are arranged side by side and closely adjacent to each other, it is possible for a single operator to reach a large number of such terminals for placing carriers therein without rising from her place and without undue exertion.

If, however, the business should increase so that a single operator could not care for it, additional operators may be located at the adjacent stations and as the arriving carriers are deposited upon the table 9 within easy reach of either of the operators, it is possible for all of the operators to work at a uniform speed without reference to the number of carriers being received from any particular outlying station. Furthermore, as all of the despatch terminals are arranged closely adjacent to each other, it is possible

to mount more of such terminals in the same desk space than has heretofore been thought possible in central station apparatus of this type.

The arrangement of the despatch and delivery terminals of each pair in the same vertical plane and one in front of the other eliminates many of the turns or bends commonly thought necessary in central station apparatus and permits the several tracks to approach the station at different levels without interference and without making it necessary to employ crossovers for connecting the tracks with the proper sending or delivery terminals. The device may thus be installed in situations where it would not be possible to install central station apparatus of the usual type, and regardless of the situation, the cost of installation is greatly reduced by the simplicity of the structure and the ease with which it may be installed.

In Figs. 10 and 11 a slightly modified form of the apparatus is illustrated. In these figures the desk is indicated at 60 and comprises the working table 67, the till receptacle 68 and the carrier receiving shelf 69. The rear edge of this shelf is defined by the panel 72 and to the rear of this panel a second panel 73 is arranged. Another panel 74 is spaced from the panel 73 to define the carrier receiving channel 75.

As in the previously described structure, the floor of the carrier receiving channel consists of two oppositely moving endless belts which convey carriers deposited thereon toward opposite ends of the desk, such carriers are then moved forwardly and onto belts which deposit them upon the table 69 in the same manner as above described.

In this instance, the lower tracks 136^b terminate in the channel 75 in the same manner as the corresponding tracks of the first described modification. The upper tracks or rails 136^a extend forwardly and are bent at 80 to provide substantially vertical portions 110 whose lower ends are secured at 81 to a shelf or bracket 82 mounted on the upper edge of the panel 72. The vertically disposed portions of the rails 136^a are spread apart near their lower ends to provide the carrier receiving opening 48^a.

The carrier driving cable comprises the run 51^a parallel to the lower rails 136^b and is guided over a pulley 52^a from whence it passes downwardly at 53^a to the driving pulley 54^a. The cable then passes up between the panels 72, 73 and over a guide pulley 55^a. From this pulley it passes downwardly and forwardly beneath a guide pulley 56^a mounted on the shelf 82 and thence in a vertical run 57^a immediately to the rear of the opening 48^a and substantially parallel to the vertical portions of the rails 136^a. By properly designing the parts, pulley 55^a may be dispensed with, if desired. The cable 130

then passes about a guide pulley 58^a whose periphery is substantially concentric with the curved portion 80 of the rails 136^a and after passing about this pulley the cable extends in a horizontal run 59^a parallel to the rails 136^a to the sending station. Manifestly, if desired, the despatch openings 48^a might be arranged at the side of the terminal structure rather than directly in the front 10 of the latter, such an arrangement being preferred in some situations and by some operators.

While the delivery and despatch terminals of but one set of tracks has herein been 15 specifically described, it is to be understood that the tracks communicating with the other sub-sending stations will be furnished with similar terminal facilities.

Although, as herein disclosed, the invention 20 is illustrated as embodied in a cable type carrier despatch system, many of its desirable features are equally applicable to systems of other type, and it is contemplated that while the term "track" has herein been 25 employed in describing a cable type track, it is equally applicable to tracks such as pneumatic tubes, etc., along which carriers move to and from the central station.

I claim:

30 1. A central station unit comprising an elongate table having an operator's station disposed at one side thereof, a row of carrier delivery terminals disposed at the other side of the table, means for causing carriers dis-

35 charged from said terminals to move forwardly into line with the table, and a constantly moving conveyor for receiving and transferring the carriers longitudinally of the table toward its central part.

40 2. A central station unit comprising an elongate table having an operator's station at one side thereof, a plurality of delivery terminals at its opposite side, means for conveying carriers discharged from said terminals in a path substantially parallel to the table, means for diverting carriers from said path and causing them to move forwardly substantially into line with the table, and means for moving the carriers along the 50 table toward the center thereof.

55 3. A central station unit comprising an elongate table having an operator's station at one side and a row of delivery terminals at its opposite side, means for receiving carriers delivered by said terminals and for moving said carriers in a path substantially parallel to the table and behind the latter, means permitting the carriers to move forwardly from said path, and means for moving the carriers along a path extending lengthwise of the table.

60 4. A central station unit comprising an operator's station, an elongate support within convenient reach of said station, means 65 for delivering carriers onto said support

from either end thereof, and a bank of cable despatch terminals disposed above said support, each of said terminals having a carrier receiving opening within convenient reach of the operator at said station, the plane 70 of the several openings being substantially horizontal.

5. A central station unit comprising an operator's station, a table within convenient reach of said station upon which carriers are 75 delivered, and a bank of cable despatch terminals disposed above the table each having a horizontally extending run of cable associated with it, and a carrier receiving opening permitting a carrier to be engaged with 80 said run of the cable, the several openings being disposed within reach of an operator seated at said station.

6. A central station unit comprising an operator's station, a bank of despatch terminals within convenient reach of the operator's station, a delivery terminal corresponding to each despatch terminal, said delivery terminals terminating in a vertical plane to the rear of the bank of despatch terminals, 90 and common means for directing all arriving carriers to a position immediately below the bank of despatch terminals.

7. A central station unit comprising an operator's station having an elongate table 95 in front of it, a bank of carrier despatch terminals directly above the table and within reach of the operator's station, a row of delivery terminals behind the table, and means for causing arriving carriers to move 100 forwardly onto the table and to a point below the despatch terminals.

8. A central station unit comprising an operator's station, a row of despatch terminals having their carrier receiving openings 105 within reach of the operator's station, a row of delivery terminals behind and parallel to the row of despatch terminals, and common means for causing carriers arriving through all of the delivery terminals to move forwardly to a position where they may conveniently be reached by an operator at the station.

9. A central station unit comprising an operator's station, a despatch terminal having its carrier receiving opening arranged within convenient reach of an operator at the station, a delivery terminal from the end of which arriving carriers are freely discharged, said delivery terminal being 110 disposed to the rear to the despatch terminal, and means for causing carriers discharged from the delivery terminal to move forwardly into reach of an operator at the station.

10. A central station unit comprising an operator's station, a plurality of pairs of delivery and despatch terminals corresponding to outlying sending stations, the delivery terminal of each pair being disposed di- 115 120 125 130

- rectly behind its corresponding despatch terminal, and means for receiving all carriers discharged from the delivery terminals and bringing such carriers to rest in 5 a position where they are within convenient reach of an operator at the station. 70
11. A central station unit comprising an elongate support having an operator's station at one side thereof, means for moving 10 arriving carriers in a path lying above the plane of the support and on the opposite side thereof from the operator's station, a deflector for diverting carriers from said path, a chute for directing diverted carriers 15 toward the plane of the table, and means for receiving carriers from the chute and moving them onto the table. 80
12. A central station unit comprising an elongate support having an operator's station at one side and means at its opposite side for moving arriving carriers in a predetermined path away from the operator's station, a deflector for diverting carriers from said path, and a conveyer belt arranged to deliver such diverted carriers onto the table. 85
13. A central station unit comprising an operator's station, a bank of despatch terminals within reach of the station, a row 30 of delivery terminals behind the despatch terminals, a belt conveyer for receiving carriers from the delivery terminals and moving them in a predetermined path away from the operator's station, a second belt conveyer for moving carriers toward the operator's station, and means for transferring carriers from the first to the second belt. 90
14. A central station unit comprising an elongate table, an operator's station at one 40 side of the table, a row of delivery terminals extending substantially parallel with the table at the opposite side thereof, an elevated belt conveyer for receiving carriers discharged from the terminals and moving them away from the center of length of the table, a second belt conveyer moving substantially in the plane of the table and toward the center thereof, an inclined chute leading from the first to the second conveyer, and a deflector for diverting carriers from the first belt into the chute. 100
15. A central station unit comprising an elongate open trough and a series of delivery terminals arranged to discharge carriers into the trough, an elongate table arranged in front of and below the trough, despatch terminals disposed above the table, each despatch terminal corresponding to one of the delivery terminals, an operator's station at the side of the table within reach of all of the despatch terminals, conveyer belts for moving carriers toward opposite ends of the trough, deflectors for diverting the carriers from the trough, forwardly inclined chutes by which the diverted carriers are 50 guided substantially to the level of the table, and conveyer belts receiving the carriers from the respective chutes and moving them onto the table from opposite ends thereof. 105
16. A central station unit comprising a support for carriers, an operator's station at one side of said support, an open trough at the other side of the support, a series of delivery terminals from which arriving carriers are discharged into the trough, means for moving carriers toward an end of the trough, means for deflecting carriers laterally from the trough, and means for receiving the deflected carriers and moving them onto the support and in front of the operator's station. 110
17. A central station unit comprising a table, an operator's station at one side thereof, an open trough extending longitudinally of the table at its opposite side, a series of delivery terminals disposed to discharge carriers into the trough, a pair of belt conveyers constituting the floor of the trough, means for moving the conveyers oppositely 95 and away from the center of the trough, deflectors for diverting carriers forwardly from each belt conveyer, and conveyers for moving such deflected carriers onto the table from opposite ends of the latter. 115
18. A central station unit comprising an elongate open trough, a row of delivery terminals extending along the trough and discharging carriers into the latter, said terminals being arranged in two groups having 100 their ends directed toward opposite ends of the trough respectively, and means for moving carriers discharged from terminals of the respective groups toward opposite ends of the trough. 120
19. A central station unit comprising an elongate open trough, belt conveyers having runs constituting the floor of the trough at opposite ends thereof respectively, said runs moving oppositely toward the ends of the trough, and two groups of delivery terminals arranged to discharge carriers into the trough, and onto the respective belts. 110
20. A central station unit comprising an operator's station serving a plurality of sending stations, a delivery and a despatch track approaching the operator's station from each of the sending stations, one track of each pair being disposed directly above the other, a delivery terminal corresponding to each delivery track and a despatch terminal corresponding to each despatch track, the several delivery and despatch terminals being arranged in parallel rows respectively 125 at the operator's station. 120
21. A central station unit comprising an operator's station, an elongate support for carriers at said station, a pair of elevated tracks extending at an angle to the length of 130

the support, one of said tracks being vertically above the other, the upper track having despatch terminal portions provided with a carrier receiving opening within convenient reach of the operator, and the lower track having a delivery terminal portion disposed directly behind the despatch terminal and from which arriving carriers are freely discharged.

10 22. A central station unit comprising an operator's station, a plurality of pairs of elevated tracks corresponding respectively to a series of sending stations, the several tracks being disposed at different heights

and one track of each pair lying vertically 15 above the other, a delivery terminal corresponding to one track of each pair and a despatch terminal corresponding to the other track of each pair, said despatch terminals and delivery terminals being arranged 20 in parallel rows with the despatch terminals in front of the delivery terminals and within convenient reach of the operator's station.

Signed by me at Boston, Mass., this 24th 25 day of April, 1923.

JOHN J. REGAN.
